UNITED STATES PATENT OFFICE.

JOHN T. HOPE, OF KANSAS CITY, MISSOURI, ASSIGNOR TO JOHN FRANK HOPE, OF KANSAS CITY, MISSOURI.

DRYING APPARATUS.

1,299,470.

Specification of Letters Patent.

Patented Apr. 8, 1919.

Application filed July 18, 1917. Serial No. 181,275.

To all whom it may concern:

Be it known that I, JOHN T. HOPE, a citizen of the United States, residing at Kansas City, in the county of Jackson and 5 State of Missouri, have invented certain new and useful Improvements in Drying Apparatus; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to drying apparatus and more particularly to a truck or rack for supporting material in dry-kilns, the principal object of the invention being to support sheets of material in such spaced relation that air may circulate therebetween, and to hold the sheets in a manner to permit them to contract while seasoning without cracking or splitting.

It is also an object of the invention to 25 provide suitable supporting standards for carrying spacing bars upon which the sheets are supported and for spacing the bars in groups to relieve the sheets of the weight of superimposed groups.

30 In accomplishing these and other objects of the invention, I have provided improved details of structure, the preferred forms of which are illustrated in the accompanying drawings, wherein:

35 Figure I is a perspective view of a dry-kiln rack containing my improvement, showing a number of flat sheets in place and illustrating a number of the supporting bars in inoperative position.

40 Fig. II is an enlarged, detail perspective view of a corner of the rack, particularly illustrating portions of standards and groups of supporting bars in their grouped, spaced relation.

45 Fig. III is a transverse vertical section of the rack.

Fig. IV is a plan view of the same.

Fig. V is an enlarged, detail perspective view of one of the standard bars, particularly illustrating the pivot pin.

Fig. VI is a similar view of a modified

form of bar, particularly adapted for mounting curved veneer or other sheets, such as barrel staves, etc.

Fig. VII is a detail perspective view of a 55 preferred type of truck operating handle.

Fig. VIII is a detail perspective view of a standard clamp.

Referring more in detail to the drawings:

1 designates track rails which may be located within a suitable dry-kiln (not shown) and a truck frame 2, comprising longitudinal side bars 3 and transverse end and intermediate bars 4—4', all of the bars being preferably of channel iron construction to 60 provide desired rigidity without excessive weight. The intermediate bars 4—4' preferably comprise spaced, paired members 5—5' for accommodating flanged wheels 6 that ride on the track rails 1, so that the 70 rack may be moved conveniently within the kiln. The truck may be suitably braced by angle irons or other bars 7, and the corners are preferably strengthened by plates 8 that may be riveted, or otherwise rigidly attached 75 to the abutting longitudinal and transverse frame bars.

10 designates standards which rise from one side of the truck and are preferably adjustably connected with the longitudinal 80 frame bar 3 by clamps 11, each constituting a body portion 12 that stands out from the frame bar and comprises upper and lower fingers 13—13', the upper fingers having 85 downturned lips 14 thereon overlying the inner edges of the channeled bar and the lower fingers having corresponding, upturned lips 15.

To assemble the clamp and standards on the frame, the clamp fingers are arranged 90 over the longitudinal frame bar, the lower end of the standard located therebetween and the halves of the clamp and standards connected and held together by bolts 16, to hold the standard firmly and without lost 95 motion thereto while permitting free longitudinal movement of the clamp along the bar, thereby adapting the truck for different lengths of veneer or other material to be dried.

100 Each of the standards comprises a body 17 and a rack plate 18 on the inner edge of the

body, having downset sockets 20 for receiving the pivot pins of material supporting bars 21, presently described, the number of standards employed depending on the 5 length of the rack and the character of material to be dried, a minimum number of standards adapting the rack for use with different lengths of material because of the adjustability of the standards heretofore 10 described.

Each of the standards is adapted for carrying a plurality of the material supporting bars 21, each of which preferably comprises side members 22-22', separated by spacing blocks 23-24 that may be anchored between the side members by rivets, or the like, 25, and an intermediate spacing block 26; all of the spacing blocks being of such width that the inner surfaces of the side members 20 22-22' are held apart a distance slightly greater than the thickness of the standards 17 so that the rack bars may be located over the standards and moved vertically therealong.

25 Carried by, and extending through the slot between the side members 22-22' of each of the rack bars 21, is a pivot pin 27, arranged at one side of the longitudinal center of the bar so that when the bar is supported 30 on the pin the center of gravity will be so located that the bar will tip. While the bars 21 may be of any suitable size and contour, they should be of sufficient length to extend practically across the truck and of sufficient 35 depth to space the material carried thereon so that air may circulate freely between the sheets of material, and while the bars are usually plain on their upper and lower edges, it may be desirable, as when the truck is to 40 be used for drying curved pieces, such as barrel staves or the like, to shape the bars for receiving such material. A rack bar of this character is illustrated in Fig. VI, showing a number of concave seats in its upper 45 and lower edge, within which transversely curved staves or the like, may seat.

In order that the truck may be moved conveniently into or from the kiln and over the track rails 1, I provide one of the end cross 50 bars 4 with handles 28, and also preferably provide an operating device 29, comprising a frame, having hooks 30 at its lower corners for taking into the handles 28, whereby the truck may be pulled or pushed along the 55 track rails.

While under normal condition the rack bars are supported in stacks on the respective standards, it is desirable, in some cases, to space the bars in groups in order to avoid 60 excess weight on the drying material. This is accomplished by providing the standards with apertures 32, within which pins 33 may be located to be engaged by the lower edges of superimposed rack bars to retain the bars 65 cut off contact with the upper bars in the next

lower groups, and thereby relieve the sheet material at the bottom of the pile of pressure which would otherwise be exerted thereon by the superimposed sheets and which might be sufficient to cause uneven contraction and cracking or splitting of the material.

70 In using the truck, assuming the same to be constructed and assembled as described, and the standards arranged at proper intervals at one side of the truck and with the rack bars on the respective standards supported at the upper ends thereof, when the material is to be located within the kiln the first sheet, or layer of sheets, is laid on the truck frame 80 and the lower rack bar in each set disconnected from its supporting standard and lowered until its lower edge contacts with the upper surface of the material. With all of the lower rack bars in this position a succeeding sheet is laid on the top of the alining rack bars and the next series of bars located on the top of the second sheet, this process being continued until the stack 85 has been built up and all of the rack bars utilized or until all of the sheets to be dried have been properly located on the truck. With the sheets so positioned the truck is moved into the kiln and the drying process carried on in the usual manner.

90 Assuming that all of the rack bars have been utilized, when the drying has been completed the truck is removed from the kiln and the material removed from the truck in the following manner:

95 The rack bars of the upper series are lifted from contact with the top sheet of the stack and slid upwardly on their standards until the top sheet has been cleared. The rack bars are then moved longitudinally until 100 their pivot pins 27 are located in upper notches 20, in the corresponding standards when the bars are released and the pins being off center, the outer ends of the bars will 105 overbalance the inner ends and cause the 110 bars to assume the inclined position illustrated in Fig. I, the spacing blocks 26 engaging the rack plates above the pivotal points of the bars to limit the tipping movement of the bars and holding the bars in the 115 elevated and inclined position while the next lower sheet, or series of sheets, is being removed from the stack. This process is continued until all of the sheets have been removed, leaving the rack in position for a 120 succeeding use.

If, on the next operation of the rack, sheets of different length are to be dried, the standards may be adjusted longitudinally along the rack until the rack bars are properly located for the different length of material, 125 when the unloading process just described is reversed to reload the truck. Should it be desired to dry sheets of unequal length, it is only necessary to adjust the standards for 130

the various lengths, so that the ends of abutting sheets will come beneath the vertical planes of the rack bars. In this way when a rack bar is lowered, one of the spaced bars 5 will contact the upper surface of one sheet and its paired bar the upper surface of the abutting sheet, or, if the sheets are of such unequal length that it is impossible to locate the abutting ends beneath the rack bars, the 10 ends may be located between adjacent sets of bars and the bars merely allowed to contact the bodies of the sheets between the ends.

In order to avoid binding sheets of very thin material under the weight of superimposed sheets, and the resultant uneven contraction, it is desirable to relieve the sheets at the bottom of the stack from the weight of those thereabove. This is accomplished by locating the pins 33 within the 20 apertures 32 in the standards at such vertical intervals that the sheets are arranged in groups of such number that their combined weight will not have the undesirable binding effect on sheets therebeneath that 25 would prevent the under sheets from contracting evenly without cracking or splitting.

When the rack bars are arranged in groups as described, they are only supported 30 at the standard ends of the bars, the free ends resting on the opposite edges of the material throughout the height of the stack, so that at one edge of the stacks the sheets 35 rest one upon the other throughout the entire height.

Having thus described my invention, what I claim as new therein and desire to secure by Letters Patent, is:

1. In combination with a standard having 40 upwardly opening notches, a slotted rack bar movable vertically and transversely along the standard and having a supporting member at one side of the center of the bar, engageable in the standard notches to support 45 the bar in an inclined plane.

2. In combination with a standard having upwardly opening notches, a slotted rack bar movable vertically and transversely along the standard and having a supporting member 50 at one side of the center of the bar, engageable in the standard notches to support

the bar in an inclined plane, and means for limiting inclination of the bar.

3. In combination with a standard comprising a supporting member, a rack bar 55 movable along the standard, having a transverse pin at one side of its longitudinal center adapted for engagement with the supporting member, and a stop on said bar for engaging the standard to limit inclination 60 of the bar.

4. In combination with a standard, a rack bar comprising side members and means for spacing the side members to form a slot of substantially the width of the standard, a 65 pin carried by the side members and projecting through the slot, means on the standard for seating the pin to support the bar, one of the spacing means being located adjacent the pin to engage the standard, for 70 the purpose set forth.

5. In combination with a frame bar, clamp members, each comprising a body part adapted for movement along one face of the bar, arms at opposite ends of the 75 body movable along the top and bottom of the bar and having inturned lips for slidably anchoring the body members and arms to the bar, a standard having its lower end located between the clamp members, and 80 rack bars slidably mounted on the standard.

6. In a device of the class described, a base frame, notched standards movable along the edges of said frame, rack bars having center slots through which said standards project, said rack bars being movable longitudinally in one direction to engage the notches in the standards in tilting relation and movable in another direction to disengage from 85 said notched standards. 90

7. A base frame, notched standards adjacently secured to the base frame, rack bars having center slots through which the standards project and notch engaging means on the rack bars adapted to engage with and 95 disengage from the notches in the standards, said engagement being effective in permitting tilting of the rack bars with respect to the base and standards.

In testimony whereof I affix my signature. 100

JOHN T. HOPE.
